PINION FOR CLOCKS AND THE LIKE AND
PROCESS OF MAKING THE SAME

Richard H. Whitehead, New Haven, Conn.

Application December 19, 1935, Serial No. 55,161

6 Claims. (Cl. 219—10)

This invention relates to pinions for clocks and the like, and the process of making the same.

It is an object of this invention to provide a new and improved method of making a pinion for clocks which will be inexpensive and suitable for quantity production and yet which will result in a rigid, accurate and reliable pinion.

Other objects of the invention will in part be obvious and will in part appear hereinafter.

This invention accordingly comprises the several steps and relation and order of one or more of such steps with respect to each of the others, and the article possessing the features, properties, and the relation of elements, and the scope of the application of which will be indicated in the claims.

For a fuller understanding of the nature and objects of the invention, reference should be had to the following detailed description, taken in connection with the accompanying drawings, in which:

Figure 1 is a side elevation of a pinion during the process of construction.

Figure 2 is a similar view with the tools used in carrying out the first step in the process in the act of being removed.

Figure 3 is a similar view of a slightly modified construction with an end plate in place.

Figure 4 is a plan view of a pinion in its completed state.

Figure 5 is a plan view of the tool used in the construction of the pinion.

Figure 6 is a plan view of the pinion shown in Figure 3.

Figure 7 is a side elevation of a modified form of pinion. Figure 8 is a longitudinal section and Figure 9 is a cross section of the same on the line 9—9 of Figure 8.

Figure 10 is a longitudinal section of a further modification.

In the making of pinions for clocks, it has heretofore involved expensive machines which individually drill holes for the various pins and insert the pins one at a time placing them by means of a dividing head which results in a relatively high cost of manufacture and which requires the maintenance of a high accuracy in the machinery in order that the errors in the resultant pinions might not be beyond the permissible tolerance.

In accordance with this invention, these various steps are dispensed with and the pins are automatically spaced and fastened in place by a single operation. To achieve this there is

forced upon the shaft 10 a collar 11 which may comprise a circular disc of soft steel or iron which is a driving fit upon the shaft to retain the pinion in place. Next there is inserted upon the shaft 10 a cylindrical tool or block 12, having a central opening 13 affording a tight but slide fit upon the shaft 10 and a plurality of circumferentially spaced openings 14 adapted to receive and accurately to position the various pins which are to comprise the pinion. The block 12 is then moved along the shaft to a point adjacent to but not in contact with the collar 11 and in each of the holes 14 is inserted a pin 15, the holes 14 being so spaced that the pins 15 will be in proper position around the shaft to form the pinion.

The block 12 is arranged to insulate the pins 15 from the shaft 10 except through the collar 11. It is either of an insulating material such as bakelite or else it contains an insulating material between the pins and the shaft so that the pins are not short circuited to the shaft by means of the block 12. After the pins are inserted in the block 12, a head 16 comprising a welding electrode is inserted over the shaft 10 but insulated from it so as to contact with the ends of each of the pins 15. This electrode, however, is made of a material which will not weld to the pins. Thereafter, while the electrode is firmly held against the ends of the pins, an electric current from any suitable source, here diagrammatically illustrated as a generator 17, is passed between the electrode 16 and the collar 11 so that the pins 15 and the collar 11 where they are in contact with each other are heated to welding temperature, whereupon the electrode 16 is pressed against the ends of the pins firmly to weld them to the collar. As soon as the welding is completed, the electrode 16 and the block 12 may be removed.

In the form of the invention shown in Figures 7, 8, and 9, a shaft 20 is turned about its pivots to form accurately concentric shoulders 21 and 22 of a diameter equal to the pitched diameter of the finished pinion less the diameter of the pinion pins. Between these shoulders, the shaft is cut away as shown at 23 to provide a clearance for the ends of the teeth of the mating gear. The pins 24 forming the teeth of the pinion are laid upon the shoulders 21 and 22 and welded in place. These pins may be spaced from each other with a dividing head or they may be spaced by a suitable jig.

In the form of the invention shown in Figure 8

10, there is provided upon the outside of the shaft 30 a pair of spaced collars 31 and 32 which are turned upon the outside to a diameter equal to the pitched diameter of the final pinion less the 5 diameter of the pins to be used. Upon these collars the pins are welded as shown in the modification of Figures 7 and 8.

The modifications shown in Figures 7 to 10, possess the distinct advantage that they have a 10 minimum outside diameter compared to the pitched diameter and hence they may be placed in a gear train with the maximum compactness and convenience.

The pinion resulting from the foregoing process is accurate and rigid by reason of the fact that each of the pins is firmly welded to the collar and has been held in its accurate position until it has cooled sufficiently to prevent displacement.

By reason of the fact that the parts are welded 20 together, for most purposes, it would be unnecessary to provide any support for the outer ends of the pins. It will thus be seen that by this simple welding operation all individual drilling for the pins is dispensed with and brass spools or brass 25 collars are unnecessary. Thus the cost of the pinion is very greatly reduced.

Since certain changes in carrying out the above process and certain modifications in the article which embody the invention may be made without departing from its scope, it is intended that 30 all matter contained in the above description or shown in the accompanying drawings shall be interpreted as illustrative and not in a limiting sense.

35 It is also to be understood that the following claims are intended to cover all of the generic and specific features of the invention herein described, and all statements of the scope of the invention which, as a matter of language, might 40 be said to fall therebetween.

Having described my invention, what I claim as new and desire to secure by Letters Patent, is:

1. The method of making pinions for clocks and the like which comprises forming upon a rotatable member, shoulders, concentric with the 45

axis of rotation of said rotatable member, and welding to said shoulders at circumferentially equally spaced points, pins for forming the teeth of the pinion.

2. The method of making pinions for clocks and the like which comprises forming upon a rotatable member, shoulders, each having a peripheral surface concentric with the axis of rotation of said member and welding a plurality of pins to said peripheral surface at equally spaced points 10 to form the teeth of the pinion.

3. The method of making pinions for clocks and the like which comprises forming upon a rotatable member, shoulders, concentric with the axis of rotation of said rotatable member, there 15 being formed also between the said shoulders a groove to give clearance for the ends of the teeth of said gear, and welding to said shoulders at circumferentially equally spaced points, pins for forming the teeth of the pinion.

4. The method of making pinions for clocks and the like which comprises forming upon a rotatable member, shoulders, each having a peripheral surface concentric with the axis of rotation of said member, there being formed also between the said shoulders a groove to give clearance for the ends of the teeth of said gear, and welding a plurality of pins to said peripheral surface at equally spaced points to form the teeth 25 of the pinion.

5. The method of making pinions for clocks and the like which comprises cutting a shaft away to form shoulders concentric with the axis of rotation of the shaft and forming a groove 30 between said shoulders to provide a clearance for the teeth of a mating gear and welding pins to the periphery of said shoulders to form the teeth of the pinion.

6. A pinion for clocks and the like comprising a 35 rotatable member having shoulders thereon separated by an intermediate groove and pins concentrically welded around said collar to form the teeth of the pinion.

RICHARD H. WHITEHEAD. 45
